US00D685318S

(12) **United States Design Patent**
Obata

(10) **Patent No.:** **US D685,318 S**
(45) **Date of Patent:** **** Jul. 2, 2013**

(54) **RECHARGEABLE BATTERY**

(75) Inventor: **Shinichi Obata**, Tokyo (JP)

(73) Assignee: **Sony Corporation**, Tokyo (JP)

(**) Term: **14 Years**

(21) Appl. No.: **29/421,388**

(22) Filed: **Jul. 16, 2012**

Related U.S. Application Data

(63) Continuation of application No. 29/371,731, filed on Aug. 5, 2011, now Pat. No. Des. 665,340, which is a continuation of application No. 29/371,062, filed on Oct. 6, 2010, now Pat. No. Des. 654,850.

(57) **CLAIM**

The ornamental design for a rechargeable battery, as shown and described.

DESCRIPTION

FIG. 1 is a front, top, right perspective view of a rechargeable battery showing my new design;

FIG. 2 is a front, bottom, right perspective view thereof;

FIG. 3 is a front elevational view thereof; and,

FIG. 4 is a bottom plan view thereof.

Portions in broken lines are for illustrative purposes only and form no part of the claimed design.

1 Claim, 4 Drawing Sheets
